ANTIAIRCRAFT FIRE CONTROL SYSTEM

Earl W. Chafee, Brooklyn, N. Y., assignor to Sperry Gyroscope Company, Inc., Brooklyn, N. Y., a corporation of New York

Application February 21, 1936, Serial No. 65,125
In Great Britain January 23, 1936

15 Claims. (Cl. 235—61.5)

This invention relates to a means for directing antiaircraft gun fire. More particularly, it constitutes an improvement and further development of the antiaircraft fire control system disclosed in my prior United States patent application now Patent #2,065,303, dated December 22, 1936, for Fire control system, joint with Hugh Murtagh and S. G. Myers, which is generally referred to as the plan projection system of fixed rectilinear coordinate axes. The system described in said patent is particularly adapted for land batteries, and the purpose of the present invention is to modify and adapt such system to a naval antiaircraft system while retaining the advantages of simplicity and accuracy characteristic of this system.

A further object of the invention is to improve the aforesaid system so that it is adapted for gliding targets as well as targets flying substantially horizontally.

According to my present invention, I propose to retain the system of rectilinear coordinates along axes fixed in azimuth with reference to a datum line such as a north-south line, for the resolution of the present ground course of the target into components from which the rate of movement along each coordinate axis is obtained. In order to use this system on shipboard, I propose to feed into the director true or absolute azimuth (or compass) angles and true or absolute elevation angles with respect to the horizontal instead of relative train angles and relative elevation angles with respect to the ship's fore and aft line and plane of the ship's deck, respectively. In order to do this, I provide a correction

device which resembles a trunnion tilt corrector and may be of the form shown in prior application, now Patent #2,069,417, dated February 2, 1937, for Fire control systems, of Murtagh and Wittkuhns, said device being controlled in both azimuth and elevation by the gyro-compass and gyro or other vertical used, and operating to stabilize in both azimuth and elevation the line of sight of the range finder or other sighting device. I supply continuously to the computer the true present elevation angle (E_0), the true present sight angle (A_0), and the present slant range (D_0). From E_0 and D_0 , I obtain the present horizontal range (R_0) and the altitude (H_0) by means of a computing mechanism which first converts the angle E_0 into the cotangent function of the angle. Two three-dimensional cams are translated according to said cotangent E_0 and are rotated from a shaft, whose motion eventually becomes proportional to H_0 , to solve for the two unknowns, horizontal range (R_0) and altitude

(H_0), by matching a dial turned from the lift of one cam pin with a dial turned in accordance with D_0 , corresponding indications on the two dials showing that the rotation of the cams is proportional to altitude (H_0). The lift of the pin on the second cam gives R_0 , which is fed into the machine substantially as the horizontal range is fed in in the aforesaid prior Patent 2,065,303, and resolved into components along rectangular axes, and the rate of change of each component measured, from which the future position is obtained by multiplying said rates by the time of flight of the shell and adding the component changes of position thus obtained to the coordinates of the present position.

In case the altitude is changing, the dial actuated from the lift pin on the first mentioned cam will not stay matched with the slant range dial D_0 as elevation angle alone is fed in, and therefore the operator must also feed in the changed altitude. Preferably a variable speed drive is arranged to set in the continuously changing altitude to keep the D_0 dials matched. In such case, the rate of change of altitude is derived, which is also multiplied by the time of flight of the shell to determine the change in altitude as well as the change in azimuth during that period.

The above combination of the two three-dimensional cams indicates when a target is not flying horizontally and also provides a means for separating that part of the change in E_0 due to change in altitude from the change in E_0 due to change in position in the horizontal plane.

According to my invention, operation of the system remains unaffected by the course, roll and pitch and yaw of the ship, since the lines of sight of the observing telescopes are stabilized. A correction for ship's speed is introduced in the same manner as the wind correction in the aforesaid prior patent, namely, it is treated as a wind blowing with equal and opposite velocity to the ship's speed and is set in as an additional wind correction on the tachometer dials showing the resolved target's speed N—S and E—W.

For targets at low angular elevation, i. e., small E_0 , a supplemental device may be provided, working on another function of the angle E_0 instead of the cotangent function.

After the future position of the target in azimuth and elevation is obtained by the rectilinear coordinate system, the computer reconverts said position into absolute future bearings and absolute future or quadrant elevation after the manner disclosed in the aforesaid Patent 2,065,303.

Since, however, the gun is trunnion mounted on the ship's deck, it is necessary to again convert the absolute angles in azimuth and elevation with respect to the fore and aft line of the ship and the plane of the ship's deck. To effect this re-conversion, I employ a second trunnion tilt corrector device such as shown in the aforesaid Patent 2,069,417, into which is fed the future absolute angles from the computer and the compass 10 bearings and the true vertical from the gyro-compass and the gyro-vertical, respectively. Said second corrector therefore sends to the gun quadrant elevation from the ship's deck and train angle with respect to the ship's fore and aft line, the 15 gun being set therefrom either by the follow-the-pointer system or automatically. By this method of obtaining the absolute or true elevation for the line of sight and for the gun elevation from the same gyro-vertical, any minor error from the 20 true vertical in said gyro has no effect on the true positioning of the gun.

In the drawings,

Figs. 1—A and 1—B are a diagrammatic representation of a computer constructed according to 25 my invention, part of the same being shown in 1—A and the second part in 1—B.

Fig. 2 is a diagram representing the position of the computer in the complete naval fire control system.

30 Fig. 3 is a diagram representing the trigonometry of the problem involved, in three dimensions.

Fig. 4 is a diagrammatic development of one of the resolving mechanisms employed in the computer.

35 Fig. 5 is a diagram explanatory of certain features of the computing mechanism.

According to my system, the line of sight from the range finder R is stabilized both in azimuth and elevation from a gyro compass and gyro vertical through a trunnion tilt corrector or eliminator, the general scheme being shown diagrammatically in Fig. 2. In this figure, the ship's gyro compass is represented at C, the gyro vertical at V, the range finder at R and the trunnion tilt 40 error eliminator at M. As described more completely in the aforesaid Patent 2,069,417, the roll and pitch and yawing of the ship are taken out of the line of sight of the range finder through the trunnion tilt error preventer M.

50 The device M is positioned in azimuth and elevation by the range finder through transmitters T_A and T'_E on the range finder actuating repeater motors R_A and R'_E at the corrector. At the same time the compass C prevents turning of the ship 55 from affecting the same through the compass repeater motor C_R and the device is in effect stabilized from the gyro vertical V through the transmitters V₁T and V₂T thereon, actuating repeater motors V₁R and V₂R. The regenerated or 60 true azimuth and elevation angles are then transmitted from transmitters T'_A and T'_E, respectively, to maintain the line of sight on the target through repeater motors R'_A and R'_E. Transmitters T_A and T'_E also transmit the true azimuth 65 bearing angle A₀ and true elevation angle E₀ to the computer through the lines marked 1 and 2, and the slant range is transmitted from transmitter T_R through line 3.

Referring now to Fig. 1—A, the true elevation 70 angle E₀ is represented as coming in on dotted line 1 and the true azimuth angle on dotted line 2, while the slant range comes in on dotted line 3, which lines represent the electric wires leading from the several transmitters T_E, T_A and T_R on 75 the range finder to the elevation repeater motor

4, the azimuth repeater motor 5 and the range repeater motor 6, respectively. Motor 4 operates coarse and fine elevation angle indicators E₀ and E_{0'}, one being geared to rotate at a multiple of the speed of the other. Each indicator is provided with a follow-the-pointer index 7, 7', the indexes being connected to be turned from a gear sector 8 on an arm 9 pivoted at 10. This forms part of a mechanism for solving for the unknown altitude H₀ and the unknown horizontal range R₀ from the known elevation angle E₀ and the known whole or slant range D₀.

From an inspection of Fig. 3 it will be apparent that the following equations may be written:

$$(1) \quad R_0 = H_0 \cot E_0$$

$$(2) \quad H_0 = D_0 \sin E_0$$

which may also be written

$$D_0 = H_0 \cosec E_0$$

The mechanism solves for the unknowns in accordance with these equations.

The arm 9 is provided with a slot 11 with which a pin on a nut 12 engages, the nut being threaded on rotatable threaded shaft 13. Said shaft is rotated from the E₀ handwheel 14 until the indexes on the E₀ dials match the pointers. Since the distance from pivot 10 to the threaded shaft 13 is fixed, it follows that as E₀ changes, the distance of nut 12 from the right hand end of threaded shaft 13 (or more precisely, from the point at which the perpendicular through pivot 10 intersects said shaft) changes proportionally to cot E₀. If, as shown diagrammatically in Fig. 5, the scale of the mechanical representation of the present elevation triangle formed by arm 9 and shaft 13, with E₀ as the included angle therebetween, is arbitrarily made such that the fixed vertical leg (i. e., the distance of pivot 10 from shaft 13) represents the maximum target altitude for which the system is designed, (and which will be assumed, by way of illustration, to be 8,000 yards) then the base of the triangle, which is the distance of nut 12 from the right-hand end of shaft 13, is equal to the product of this maximum altitude and the cotangent of E₀ and therefore has a value equal to 8,000 cot E₀ or

$$\frac{8,000}{H_0} \times R_0$$

In other words, the base of the triangle represents R₀ on a scale which varies with altitude and is equal to R₀ when the altitude is a maximum, here taken as 8,000 yards. At the same time that it shifts nut 12 the rotation of handwheel 14 shifts laterally the three-dimensional cams 15 and 16, the shaft 14' of said handwheel being geared to the threaded shaft 17 on which a bracket 18 supporting the cams is mounted. Therefore these cams will be translated proportionally to cot E₀ and since shaft 17 is connected by gearing with shaft 13, the position of bracket 18, measured from a reference position, also represents cot E₀ on a suitable scale, and in the present case has a value of 8,000 cot E₀. The contour of cam 15 is such that as it is rotated and translated by means to be described, the lift of the cam pin 19 thereon is proportional to the slant range D₀ corresponding to the value of E₀ according to which the cam is translated and the value of H₀ according to which it is rotated (see Equation 2). The cam pin 19 therefore is connected to rotate the index 20 of the slant range dial D₀ actuated from motor 6, and it is the duty of the operator of handwheel 26 and/or 27 to maintain said pointers

matched. It is obvious that a power driven follow-up may be employed if desired. When the pointers are matched, the angular position or rotation of the cam 15 represents H_0 . Therefore the cam 16 will likewise be positioned rotationally in proportion to H_0 and it is translated proportionally to $\cot E_0$. This cam likewise is provided with a cam pin 21. This cam is so laid out that when the translation is proportional to $\cot E_0$ and the rotation proportional to H_0 , then the lift of the cam pin 21 will be proportional to horizontal range R_0 (Equation 1). Said pin is therefore shown as positioning a dial R_0 which has a follow-the-pointer index 23 on a concentric outer dial. The two cams are shown as rotated from a gear 24 and a long pinion 25 which, in turn, is set from either one or the other of the H_0 handwheels 26 or 27. The index 23 is turned from the horizontal range or R_0 handwheel 28 which turns the index through shaft 28', differential 29, shaft 30, shaft 31 and worm 32. When index 23 is matched with the pointer on the inner R_0 dial by turning handwheel 28, R_0 is set into the computer through the shafts 30 and 33.

With the foregoing arrangement it will be evident that means are provided to indicate when a target is not flying horizontally. In prior arrangements it has been recognized that changes in E_0 may be due not only to change in position in the horizontal plane but to change in altitude, but the practice has been to assume the craft to be flying at a constant level. With the above arrangement, however, the observer is enabled to separate that part of the change in E_0 due to change in altitude from the change in E_0 due to change in position in the horizontal plane, because in case the altitude is changing, the index 20 will not stay matched with the slant range dial D_0 when only the elevation angle of the target (E_0) is fed in and therefore changed altitude must also be fed into the machine through the handwheel 26 or 27. The latter is used primarily for setting up an original altitude or when the rate of change of altitude is not constant. In case the target is diving or climbing steadily, the handwheel 26 is used to set up a rate of change of altitude. This handwheel, it should be noted, positions the change speed member, i. e., ball 35, of a variable and reversible speed gear of which the disc 36 is constantly driven as from a motor 37. The ball drives a cylinder 38 which is connected through a differential 39 to the shaft 27' of handwheel 27 and to shaft 40 which rotates the pinion 25, the altitude being shown on H_0 dial 40'. At the same time the changing altitude H_0 is set into the machine through shafts 41, 42 and 43.

When the condition of constant altitude H_0 obtains, it is not necessary to position index 23 continuously by turning handwheel 28 since once this index and the pointer on the inner R_0 dial are matched, they will remain matched due to the rotation of index 23 by means now to be described. The rotation of shaft 17, measured from a reference position, as noted above, has a value of $8,000 \cot E_0$ due to the fact that 8,000 yards is the value of the vertical leg of the triangle in the cotangent solving mechanism mechanically representing the present elevation triangle as shown in Fig. 5. If, therefore, a target at 8,000 yards altitude is being tracked, the rotation of shaft 17 represents R_0 directly.

It is seen in Fig. 1—A that the value $8,000 \cot E_0$ is set into the computer by way of differential 73 geared to shaft 17, differential 29, shaft 30 and

shaft 33. By means of a nut moving along a threaded portion of shaft 42, a ball 71 bearing on disc 70, driven from shaft 17, is positioned according to altitude H_0 from shaft 41, the motion of which is controlled both by the altitude displacement and altitude rate settings of handwheels 27 and 28 respectively. Ball 71 is at the center of disc 70 when the value of H_0 is 8,000 yards. Therefore, at 8,000 yards altitude, roller 72 does not rotate and introduces no motion into differential 73 and consequently, assuming that no motion is introduced into differential 29 by way of shaft 28', the rotation of shaft 33 reproduces the rotation of shaft 17 and represents $8,000 \cot E_0$. If, however, the altitude H_0 has some value which is less than the maximum, ball 71 will be positioned away from the center of disc 70 a distance representing the difference between 8,000 yards and this value, and since the rotation of disc 70 is proportional to $\cot E_0$, the rotation of roller 72 will be proportional to $(8,000 - H_0) \cot E_0$ and by a suitable choice of constants can be made to represent this value. The output of differential 73 (with proper directions of rotation) and the rotation of shaft 33 then become: $8,000 \cot E_0 - (8,000 - H_0) \cot E_0$

$$= H_0 \cot E_0 \\ = R_0$$

It is seen that the multiplying device comprising disc 70, ball 71 and roller 72 in combination with differential 73 provides R_0 computing means operating in parallel with cam 16 and that the results of these two computations are shown on the outer and inner R_0 dials respectively.

Shaft 31, driven from shaft 30, drives through worm 32 the outer R_0 dial bearing index 23, said dial having teeth cut in its periphery, and as the rotation of shaft 31 represents range as computed by the variable speed multiplier, the R_0 pointer on the inner dial and index 23 should remain matched once they have been brought into coincidence, as for instance by rotating handwheel 28, if altitude remains constant. The distinction between the change of elevation angle due to changing range and that due to changing altitude will now be apparent since it is seen that range handwheel 28 has to be operated only if a change of elevation angle occurs due to change of altitude but not if a change of elevation angle occurs due solely to change of range.

While the cotangent solution is satisfactory for sizable angles of elevation, when the angle becomes small I prefer to use the angle itself instead of the cotangent function. To this end, the bar 9 towards its lower end is curved so that the travel of the nut 12 along the shaft 13 at low angles will be approximately proportional to E_0 . In this case the handwheel 28 is rotated until a counter 44 reads the same as the slant range dial 60 D_0 , thus taking the value of slant range D_0 and using it as horizontal range R_0 , which is sufficiently accurate for small angles. This value of R_0 is fed into the machine through shafts 30, 33, as before. It is also communicated to shaft 45 to position a threaded carriage 46 proportionally to R_0 . A pivoted arm 47 is rotated automatically from a cam surface 48 on the carriage 18 so that the angle between the arm 47 and the horizontal is a function of the angle E_0 , preferably a multiple of the small angles involved. The altitude handwheels 26 and 27 are set to position the height of the arm 49 so that vertical bar 165, one end of which bears an arm 49, has its other end in contact with arm 47 as determined by indi-

cating means not shown, the shaft 43 rotating the threaded shaft 50 on which the hub of the arm is threaded. This sets up a mechanical triangle whose base represents R_o (taken as equal to D_o), whose altitude represents H_o and whose acute base angle is proportional to E_o . H_o is the derived quantity determined by vertically positioning bar 165 from shaft 43 (through arm 49) by rotating handwheels 26 and 27 and the motion thereby imparted to shaft 43 is the value of H_o fed to the prediction mechanism.

The azimuth repeater motor 5 is similarly shown as actuating coarse and fine dials A_o and A'_o , each having a follow-the-pointer index 51 and 51'. These indices are maintained matched with the dials, preferably by handwheel 52 which rotates the shafts 55 and 56 to set the changing A_o into the machine.

As explained in the aforesaid prior Patent 2,065,303, I prefer to project the movements of the target into the plane of the ground and to resolve its ground course into x and y components, say N—S and E—W, and to obtain the rate of change along each component. To this end, I provide resolving mechanisms shown diagrammatically in Fig. 1—B at 57 and 58. These mechanisms (see Fig. 4) comprise essentially a flat disc 59 having a spiral groove in its upper surface in which engages a pin 60. Said pin also engages a slide 61 mounted in a slot 62 in a second disc 63. It also engages a slot 64 in a bracket 65 mounted for rectilinear movement only in a N—S direction, for example. The disc 63 is shown as rotated in accordance with the angle A_o from shaft 56 through shaft 57' and suitable gearing (not shown), so that the slot 62 is positioned in azimuth in accordance with the angle A_o that the line of sight makes with the N—S line. The disc 59, on the other hand, is rotated in accordance with the horizontal range R_o from shaft 33 and shaft 58' through a differential 150 also connected to shaft 57' to prevent the range being changed by changes in A_o . Therefore the slide 61 will be given a radial position in the slot proportional to R_o and its direction of displacement will be in accordance with the angle A_o . The x component of this movement, say the N—S component, will be imparted to the bar 65. The y or E—W component is imparted to a corresponding bar 65' mounted on an identical resolving mechanism 58 in which the slot 62' is maintained at right angles to the slot 62. Therefore the positions of the two bars 65 and 65' represent the x and y components of the target's position.

Means are then provided to determine the rate of movement of the target along each component, which may be done as in the prior patent by means of tachometers 66 and 66'. Periodically the movement along each component is timed by its tachometer and the rates set in by rotating the respective x and y handwheels 67 and 67' to match the indices 68, 68' thereon with the tachometer pointers.

Said rates are then multiplied by the time of flight of the shell by any suitable means, such as cams 69 and 69'. Said cams are arranged to be moved axially in accordance with the time of flight of the shell obtained from the movement of a cam pin 70' on cam T. The cams 69 and 69' are respectively rotated from the handwheel 67 through cross shaft 71' and long pinion 72 and from handwheel 67' through gearing 73' and pinion 72'. The lifts of the pins 74 and 75 on the two cams 69 and 69' are proportional to the dis-

tance the target moves along each x , y component during the time of flight of the shell. The time of flight is of course proportional to the entire or slant range, which is a function of the horizontal range and altitude

$$(D_p = \sqrt{R_p^2 + H_p^2})$$

Cam T is shown as moved axially from future altitude, the shaft 76 thereof being rotated from a gear 77 driven by an elongated pinion 78. Said pinion, in turn, is rotated from H_o shaft 43 through a differential 79, the change in height during time of the flight of the shell being added from shaft 80 to give the predicted height (H_p), as hereinafter explained. The cam is moved longitudinally from the R_o shaft 33 through a differential 81 into which is also fed the change in range from the range difference motor 82 to give predicted range (R_p). As shown, the differential 81 rotates shafts 83 and 84, the latter rotating the screw 85 to position traveling carriage 86 threaded thereon, which moves the cam axially. For convenience, the fuse setting cam F and the quadrant elevation cam QE are mounted on the same shaft 76 as cam T so as to be rotated and positioned axially therefrom. The lift of cam pin 70' on cam T is shown as shifting axially the cams 69 and 69' through a cross bar 87.

A tachometer 88 similar to the tachometers 68 and 68' may be used for determining the future altitude. Present altitude, when changing, continuously rotates the shaft 43, thereby rotating a disc 89 forming a part of a variable speed mechanism. The ball or roller 90 thereon is positioned from the time of flight pin 70' by being connected to move radially with the axial movement of the cams 69, 69'. Therefore this mechanism acts to multiply the rate of change of altitude by the time of flight of the shell, which rotates cylinder 91 at a rate proportional to the change of altitude. The cylinder 91 rotates the tachometer 88 at that rate, which therefore measures this rate and gives the change of altitude, which is set in by rotating the handwheel 92 to match the index 93 with the pointer. The value so set in rotates the shaft 80 and differential 79 to add the change in altitude that takes place during the time of flight of the shell to the present altitude, thus rotating shaft 81' and pinion 78 according to the future or predicted altitude H_p .

The cam pins 74 and 75 control mechanisms 94 and 95, which may be similar in construction to the mechanisms 57 and 58, but which act conversely thereto to convert the future coordinate positions of the target into future range and bearings. For this purpose it is desirable to provide follow-up or power driven systems for actuating the mechanisms, as described more completely in my aforesaid Patent 2,065,303. The cam pins are shown as positioning pairs of reversing contacts 96 and 96', respectively, the trolleys or brushes of which, 97 and 97', are mounted to move with the slide bars 98 and 98', respectively. The bar 98 is positioned primarily from the corresponding bar 65 of the mechanism 57 through shaft 99, but has an additional movement imparted thereto through differential 100 to introduce the change in the x position that has taken place during the time of flight. Similarly, the bar 98' is positioned from the bar 65' through a differential 100' to introduce the corresponding changes in the y position. Therefore the angular position of the discs 69 of re-

solvers 94 and 95 will represent the future range R_p and is shown as taken off through shafts 101 and 101' to rotate the shaft 83, while the angular position of the disc 63, containing the radial slot, shows the future angle A_p and is transmitted through shafts 102 and 102' to shaft 103. In practice, the shafts 83 and 103 are rotated from the range difference motor 82 to turn the discs 59 and 63 thereof and the azimuth difference motor 104, respectively, said motors in turn being driven from the contacts 96 and 96', the motors being connected to said shafts through differentials 81 and 105, respectively. Box S represents a quadrant switch more completely described in the aforesaid Patent 2,065,303. The future azimuth angle A_p is transmitted, with whatever corrections needed, through a transmitter 106 to a second trunnion tilt eliminating device M' through wires 130.

20 The quadrant elevation cam QE, it will be remembered, is positioned axially in accordance with the future horizontal range R_p , and rotationally in accordance with future altitude H_p , the cam being designed so that the lift of the pin 108 thereon gives the proper gun elevation for the type of shell employed, suitable corrections for this purpose being put in through the handwheel 109 to vary the effective length of the pin 108, and the quadrant elevation is transmitted to the trunnion tilt corrector through transmitter 110 and wires 131. Similarly, the fuse setting is derived from the cam F on shaft 76 from a lift pin 111, into which corrections may be introduced through handwheel 112, the fuse setting being transmitted from transmitter 113 and wires 132.

As in my prior patent, the wind correction is preferably introduced as a component rate correction along the xy components, this being introduced into the settings of tachometers 68 and 68'. Preferably, also, I employ a similar means for correcting for the speed and course of the firing ship. As far as the effect of the wind is concerned, the motion of the firing ship may be treated as an apparent wind in the opposite direction to the movement of the ship, and therefore this apparent wind may be resolved into xy components and corrections introduced in the same manner as the true wind. For the above purposes, I have shown two resolving mechanisms. At 114 is the resolving mechanism for the true wind. This may comprise an inner dial 116 set in azimuth by a handwheel 115 until the slide bar 116 thereon lies in the true direction of the wind, as indicated by the reading of index 151 on scale 152. Said scale is preferably made adjustable in case the xy components are not truly N—S and E—W. The bar is then adjusted by turning the pinion 117 until the length thereof to the right of the pinion represents the velocity of the wind. This velocity is then resolved into x and y components by positioning the cross hairs 118 and 119 from handles 118' and 119' until they intersect at the zero index on the bar, thereby rotating the shafts 120 and 121.

A similar resolving mechanism 122 is provided for the ship's course and speed. In this case, however, the dial 153 thereof is rotated from a repeater compass 123 so that it is maintained fixed in azimuth regardless of the turning of the ship. Slide bar 124 is adjusted in accordance with the ship's speed and the two components are then determined by means of the 75 cross bars 125 and 126, as before, by turning

handles 154 and 155. The component values of the true wind and apparent wind are then added algebraically through differentials 127 and 127' and the result led to the two tachometers 68 and 68' through differentials 128 and 128', where the xy rates are added. The indices are thus displaced, and the handwheels 67 and 67' must be rotated accordingly to keep them matched with the tachometer pointers. In my solution of the problem, the speed of the firing ship is otherwise neglected, being taken into account as the apparent speed and course of the target.

The final predicted quadrant elevation and bearings are transmitted from the computer through lines 130 and 131, but are first led 15 through a second trunnion error device M' to correct the same for trunnion tilt errors and to reconvert them into angles with respect to the ship's deck and fore and aft line before reaching the gun G. The device M' is operated identically with the device M, except that it is positioned in accordance with the trunnion position of the gun (i. e., future bearings) instead of the trunnion position of the range finder (present bearings), and into which are fed the future 25 bearings and elevation instead of the present bearings and elevation. The gun will therefore be positioned in the proper position to hit the target at all times regardless of the roll and pitch of the ship.

It will be understood that suitable indicators may be provided wherever desired throughout the instrument. For instance, I have shown a dial A_p on the future bearing transmitter 106, a dial E_p upon the quadrant elevation transmitter, and a dial F_p on the fuse transmitter. I have also shown a dial 160 connected to the range difference motor 82, indicating the range changes, and a dial 161 connected to handle 26, indicating the rate of change of altitude. 40

Also, while I have referred to the x and y axes as E—W and N—S, it will be understood that they may be taken in any direction as long as they remain fixed in azimuth during a period of fire. Preferably, the fore and aft line of the 45 ship at the time of throwing the computer into use is taken as the y axis.

As many changes could be made in the above construction and many apparently widely different embodiments of this invention could be made 50 without departing from the scope thereof, it is intended that all matter contained in the above description or shown in the accompanying drawings shall be interpreted as illustrative and not in a limiting sense.

Having described my invention, what I claim and desire to secure by Letters Patent is:

1. In an antiaircraft director for computing proper gun elevation, means to set in slant range (D_0) and the elevation angle (E_0) of the 60 target, means to compute present altitude (H_0) and present horizontal range (R_0) from said transmitted quantities of slant range and elevation angle, including means for mechanically generating a displacement proportional to the 65 cotangent of the elevation angle as one side of a rectangular triangle having its hypotenuse proportional to slant range and said elevation angle (E_0) included between said side and hypotenuse, and a pair of three-dimensional cams 70 positioned in one dimension by said displacement and in the other dimension by an arbitrary quantity until the lift of the pin on one cam is proportional to slant range, whereby said arbitrary quantity becomes proportional to present 75

altitude (H_0) and the lift of the pin on the other cam simultaneously becomes proportional to horizontal range (R_0).

2. In an antiaircraft director for gliding targets, means for continuously setting slant range (D_0) of the target into an indicator, means for continuously setting in elevation angle (E_0) of the line of sight, means to mechanically solve simultaneously for the unknown horizontal range (R_0) and altitude (H_0), comprising a pair of coaxial three-dimensional cams each having a cam pin, one cam pin adapted to match said indicator, the other cam pin adapted to operate a range dial, means to position said cams in one dimension in accordance with the cotangent function of said elevation angle, and arbitrary setting means to position said cams in the other dimension to such values of altitude (H_0) as to keep said slant range indicator matched, whereby said range dial is caused to indicate present horizontal range (R_0) and the set value of altitude (H_0) represents actual target altitude.
3. In an antiaircraft computer to which functions of target position including slant range (D_0) and elevation angle (E_0) are continuously supplied, an elevation angle indicator, a slant range indicator, a computing mechanism computing horizontal range (R_0) from said slant range (D_0) and said elevation angle (E_0), including means for arbitrarily feeding height (H_0) and horizontal range (R_0) into said computing mechanism at such a rate as to simultaneously match both of said indicators, a measure of actual target height (H_0) and actual horizontal target range (R_0) being obtained when said indicators are matched.

4. In an antiaircraft computer into which elevation angle (E_0) and slant range (D_0) are continuously supplied, an elevation angle indicator, a slant range indicator, a triangle mechanism of fixed height and variable base and an acute angle, in which said angle is kept at the elevation angle (E_0) to give a base length representing the cotangent of said angle ($\cot E_0$), a second mechanism in which said cotangent of said angle is combined with slant range (D_0) to give altitude (H_0), a third mechanism for combining the cotangent of said angle ($\cot E_0$) and altitude (H_0) to give horizontal range (R_0) on a range indicator, a fourth mechanism to also calculate said same horizontal range and connected to match said range indicator, whereby with constant altitude said range indicator remains automatically matched regardless of change of horizontal range, said indicator becoming unmatched only upon change of altitude.

5. An antiaircraft director as claimed in claim 1, in which an alternative approximate solution is employed as the elevation angle (E_0) drops below a given value, said solution being obtained by means of an assembly of members forming a triangle in which two sides are each proportional to slant range (D_0) and in which the included angle is the elevation angle (E_0).

6. An antiaircraft fire control apparatus as claimed in claim 2, having a variable speed device in said arbitrary setting means (H_0), whereby said indicator is kept matched automatically when the proper rate of change of altitude has been set up.

7. In an antiaircraft director for computing the proper gun elevation from instantaneous values of angular elevation and slant range of a target continuously transmitted from a range finder, a computing mechanism including means

for determining the future altitude and future horizontal range of said target from said range finder data, means providing an alternative solution in case of substantially horizontal fire as altitude approaches zero, one or more elements being common to said two means and said alternative solution including initially equating slant range and horizontal range, means for continuously determining gun elevation from future target positional data and means for selectively supplying said data continuously to said last means from one of said first two means.

8. Means for computing proper gun elevation for antiaircraft guns from slant range (D_0) and angular elevation (E_0), continuously supplied by a range finder, comprising cam means for continuously solving the equations R_0 (horizontal range) = $H_0 \cot E_0$ (altitude times the cotangent of the elevation angle), second cam means for simultaneously and continuously solving the equation H_0 (altitude) = $D_0 \sin E_0$ (slant range times the sine of the elevation angle), and multiplier means for a second simultaneous and continuous solution of said first named equation, whereby altitude and range are continuously obtained.

9. In antiaircraft fire control apparatus, means for continuously obtaining the altitude of a moving target from slant range (D_0) and angular elevation (E_0), continuously supplied by a range finder, comprising a first means for obtaining horizontal range (R_0) therefrom, a second means for obtaining horizontal range therefrom, means to match the output of said first means with the output of said second means comprising means to introduce arbitrary settings proportional to unknown altitude (H_0) until said outputs remain matched, whereby true altitude is simultaneously obtained.

10. An antiaircraft fire control apparatus as claimed in claim 9, having a variable speed device in said second means for obtaining horizontal range, to compensate for altitude changes.

11. In an antiaircraft fire control device as claimed in claim 2, a follow-up pointer for said range dial, second means to solve for unknown horizontal range including a variable speed drive connected as a multiplying device to multiply said values of the cotangent of said elevation angle by the difference between an assumed fixed maximum altitude and said computed altitude H_0 , differential means to combine the product with a multiple of said cotangent value proportional to said fixed altitude, and means to connect said follow-up pointer to said differential means, whereby said pointer automatically remains matched as long as said altitude H_0 remains constant.

12. In an antiaircraft fire control apparatus, an indicator to receive elevation angle E_0 of a target, a follow-up pointer associated with said indicator, a cotangent solving mechanism for said elevation angle adapted to match said pointer to said indicator, a pair of three-dimensional cams positioned in one dimension by said mechanism according to said cotangent value, a slant range receiver having a dial to indicate received slant range, a follow-up marker for said dial operated from a cam pin on one of said cams, a range dial operated from a cam pin on the other cam, a follow-up marker for said last named dial, a range solving mechanism to operate said last named marker, altitude setting means to position said cams in another dimension to match said first named marker to said first

named dial, and means to operatively connect said range solving mechanism to said cotangent solving mechanism and to said altitude setting means, whereby both said markers remain automatically matched to their respective dials as long as the value of altitude once set in remains constant.

13. In an antiaircraft fire control apparatus, means for continuously obtaining the altitude of a moving target, comprising means for feeding into the apparatus from a range finder values representing slant range (D_0) and angular elevation (E_0), means for obtaining a fictitious value representing horizontal range (R_0) in terms of a permanently fixed value of altitude (H), a pair of three-dimensional cams each having a cam pin, means for positioning both said cams in one dimension from said first named value, means for positioning both said cams in another dimension by an arbitrary setting proportional to unknown altitude (H_0), such that the lift of one cam pin is proportional to said known slant range and the lift of the other cam pin is proportional to true horizontal range (R_0), a follow-the-pointer mechanism associated with said last named cam pin, a correcting means controlled by said altitude (H_0) to correct said fictitious value of R_0 for the altitude difference ($H - H_0$), and means to introduce said corrected value of R_0 into the computer and into said follow-the-pointer mechanism, whereby said mechanism remains matched automatically as long as altitude H_0 remains constant.

14. In an antiaircraft fire control director, data converting means for deriving data including altitude (H_0) from observed data relating to the position of an aerial target, including slant range (D_0) and elevation angle (E_0), comprising an indicator for slant range, a calculating device controlled partly by a function of said elevation angle (E_0), and means for additionally controlling

said calculating device to position a part to match said indicator, said calculating device being constructed and arranged so that when said indicator is matched, the quantity set into said last named means for controlling said calculating device is thereby made proportional to the altitude (H_0) of the target. 5

15. A system of antiaircraft fire control adapted to shipboard use, comprising a range finder for measuring present slant range of a target, a sight rotatable in azimuth and elevation relative to the ship, means for continuously measuring the angular elevation and azimuth of the line of sight relative to ship's axes, means for continuously measuring the positions of said ship's axes relative to fixed axes, a first corrector for converting positional data relative to said ship's axes to data relative to said fixed axes, a second corrector for converting positional data relative to said fixed axes to data relative to 20 ship's axes, a computer for calculating future positions of said target in accordance with a plurality of factors including present slant range, angular elevation and azimuth and rates of change thereof, all relative to said fixed axes, 25 means for continuously transmitting the present angular elevation and azimuth of said target relative to said ship's axes to said first corrector, means for continuously transmitting the converted data therefrom to said computer, means 30 for continuously transmitting present slant range from said range finder to said computer, means for continuously transmitting future target position data relative to said fixed axes from said computer to said second corrector, a gun positionable in azimuth and elevation relative to said ship's axes, and means for continuously transmitting future target position data relative to said ship's axes from said second corrector to said gun. 35

EARL W. CHAFEE.
